HOLDER FOR DUPLICATE CONTRACT
BRIDGE HANDSHerman Simmonds, Jr., New York, N. Y., assignor
of one-half to Dick R. McLain, New York,
N. Y.

Application January 23, 1933, Serial No. 653,202

1 Claim. (Cl. 273—151)

This invention relates to a holder or card container for use when playing duplicate contract bridge and one object of the invention is to provide a device of this character which will not only serve as a container for the dealt hands of cards to be used in the playing of duplicate contract bridge but also a holder for a deck of cards when the same are not in use.

As is doubtless well known, the four players in the game of duplicate contract bridge are presented with dealt hands when they approach the table for play and this is true as the players progress from table to table. Usually, these cards dealt into four hands are presented to the players in holders, the hands being designated as north, south, east and west and indication made which hand is represented as the dealer, but the holders now in use are large and cumbersome and are not easily transported from place to place nor may a quantity of such holders be stored in a compact place or compartment.

It is another object of my invention, therefore, to provide a card holder which is capable of readily receiving four hands of cards, preserving them as dealt and a holder so constructed that it may be folded into small compact form.

Still another object of the invention resides in the construction of a card holder of the type mentioned which is so designed that it may be folded into such compact form that it will be substantially the same size, when folded, as the ordinary deck of cards, whereby a number of decks of cards held in such holders may be transported from place to place in a reasonably small package or container.

A still further object of the invention resides in providing a holder of the type mentioned wherein the supposed dealer's hand will be readily indicated and in addition thereto, the vulnerability of the various hands indicated by distinctive colors appearing on specific portions of the holders. By this arrangement, players taking their places at a table when progressing from one table to another may readily observe which hands are vulnerable and thereby exercise the necessary caution when bidding. Whereas at the present time, some holders for duplicate contract bridge hands are marked to indicate hands which may be vulnerable, these markings are usually in printed form so that the players may overlook those hands which are vulnerable. By providing a container wherein portions thereof hold hands which are supposed to be vulnerable and distinctively colored, the players will be constantly warned and players may proceed with the game accordingly.

A further object of the invention resides in providing a holder or container of the type mentioned, which is simple in construction, inexpensive to manufacture and one which will be very effective in use.

A container constructed in accordance with this invention is illustrated in the accompanying drawings, wherein:

Figure 1 is a top plan view showing the container in position for use and cards in place thereon;

Figure 2 is a sectional view taken along the line 2—2 of Figure 1;

Figure 3 is an end view showing the container and cards folded;

Figure 4 is a top plan view of the folded container; and

Figure 5 is a diagrammatic view of a set of containers used for playing four successive hands in a game of duplicate contract bridge.

The improved card container illustrated in detail in Figures 1 through 4 is one of a set of four containers shown in Figure 5 and in this figure designated respectively by the letters A, B, C and D. These containers are to be placed upon tables at which players successively play during a game and as many sets will be used as are necessary according to the number of tables. Each container consists of a center section or plate 1, and sections 2 and 3 designated North and South as shown at 4 and 5 by letters marked upon ends

of the center plate 1 and side sections or plates 6 and 7 designated East and West as shown at 8 and 9 by letters marked upon the center plate at opposite sides thereof. The center plates also have their central portions marked respectively with numerals 1, 2, 3 and 4 thereby designating tables upon which the containers are to be placed and in addition each container has its center plate marked with the word "Deal" located adjacent the north, east, south and west positions respectively and indicating which player is to deal when a new set of players take their positions at the table. The players move from one table to another after each hand has been played and although they occupy the same positions at the tables the deal changes with each hand and since the containers are marked with the word "Deal" there will be no danger of the wrong person dealing.

It is also important to designate which hands, if any, are vulnerable and this should be prominently called to the attention of the players. In order to do so the plates or sections are distinctively colored. These colors in the present illus-

tration are silver and gold, the gold designating vulnerable, but it is to be understood that any colors which can be easily distinguished may be used. Gold or red are preferably used to designate the vulnerable hands as these colors mean caution or danger.

Referring to Figure 5, it will be seen that the players first occupy seats at a table upon which the container A is placed. All of the card receiving sections are silver and, therefore, no hands are vulnerable. North deals and the hand is then played in the usual manner. When the hand is finished, the cards are replaced upon the sections of the container from which they were removed and the players move to the next table where they occupy the same positions and east deals the cards left there by the previous players. At this table, the north and south sections of the container are colored gold and the east and west sections silver. This indicates that north and south are vulnerable and they must be careful how they bid and play their hands. At table three, south deals and north and south sections of the container are silver whereas east and west are gold to indicate that east and west are vulnerable instead of north and south. Upon reaching table four, it will be found that all sections of the container are colored gold, thereby indicating that all players are vulnerable and each must be very careful when playing this hand. At the next table, another series is started. It will thus be seen that this improved container will indicate who deals at each table and which hands are vulnerable.

As previously explained, the containers are to serve as holders for dealt hands during play and also as a container for a deck of cards when not in use and is so constructed that the container may be folded into a compact mass together with the cards and placed upon a shelf or into a case together with a number of other decks and easily stored away or transported from one place to another. Therefore, each container is constructed as shown in Figures 1 through 4 and referring to these figures, it will be seen that the center section or plate 1 is connected with the card receiving sections by hinges 10, 11, 12 and 13. These hinges are of different lengths and have their end portions pivoted to the plates whereby the card carrying sections or plates may be folded inwardly with cards carried thereby from the extended position shown in Figure 1 to the folded position shown in Figure 3. When so folded, the section 2 is first swung inwardly into position above the center section 1 and the section 3 then swung into position upon section 2. Section 7 is then swung into place upon section 3 after which section 6 is swung into place upon section 7. Each section carries 13 cards and the hinges are of such length that a compact stack or deck of cards will be formed with the plates

or sections extending between the hands and also in covering relation to upper and lower faces of the deck. This will protect the deck as well as keeping the dealt hands separated and since the sections or plates are formed of strong but thin material such as sheet metal, celluloid, light weight wood, bakelite or other material, the deck will not be materially increased in bulk and can be easily carried in a pocket or a large number placed upon a shelf or into a case. Clips 14 formed from strips of spring metal are carried by the card holding sections and when the cards are slipped into place beneath the clips, they will be gripped and prevented from slipping out of place. Notches 15 formed in edges of the plates permit the hinges to extend flush with the edges of the plates or sections when the device is folded and in order to retain the device in its folded condition a clamp 16 is applied as shown in Figures 3 and 4 and securely but releasably holds the sections in their folded positions.

It will thus be seen that this device serves very efficiently as a container and shield for a deck of cards not in use and also as a device for holding dealt hands when playing duplicate contract bridge and indicating the dealer and which hands, if any, are vulnerable as players progress from one table to another.

From the foregoing description of the construction of my improved card holder, the method of applying the same to use will be readily understood. It will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to, without departing from the spirit or sacrificing any of the principles of the invention.

Having thus described the invention what is claimed is:

A card holder for duplicate contract bridge comprising a center leaf, side and end leaves having means for retaining dealt hands of cards stacked thereon, and hinges connecting the side and end leaves with the center leaf, said hinges being of progressively increased length whereby the side and end leaves may be swung inwardly to a folded position and disposed over the center leaf one above another with the cards in stacked formation between the leaves with the dealt hands separated by the leaves, edge portions of certain of the leaves being notched and forming seats to receive portions of the hinges and dispose outer faces of the hinges flush with edges of the folded leaves and prevent sliding movement of the leaves relative to each other when folded.

HERMAN SIMMONDS, JR.
